(57) **CLAIM**

The ornamental design for a display screen with animated graphical user interface, as shown and described.

DESCRIPTION

FIG. 1. is a front view of a first image of a display screen with animated graphical user interface showing our new design;

FIG. 2. is a front view of a second image thereof;

FIG. 3. is a front view of a third image thereof;

FIG. 4. is a front view of a fourth image thereof;

FIG. 5. is a front view of a fifth image thereof;

FIG. 6. is a front view of a sixth image thereof;

FIG. 7. is a front view of a seventh image thereof; and,

FIG. 8. is a front view of an eighth image thereof.

The appearance of the animated graphical user interface sequentially transitions between the images shown in FIGS. 1-8. The process or period in which one image transitions to another image forms no part of the claimed design.

The outer peripheral broken lines represent a display screen or portion thereof and form no part of the claimed design. The dash-dash broken lines with the boundary lines represent portions of the graphical user interface that form no part of the claimed design.

1 Claim, 8 Drawing Sheets
